UNITED STATES PATENT OFFICE.

ORLANDO F. BELCHER, OF WINTHROP, MASSACHUSETTS.

CARTRIDGE-LOADING MACHINE.

SPECIFICATION forming part of Letters Patent No. 231,753, dated August 31, 1880.

Application filed May 22, 1880. (No model.)

To all whom it may concern:

Be it known that I, ORLANDO F. BELCHER, a citizen of Winthrop, county of Suffolk, State of Massachusetts, have invented certain new and useful Improvements in Cartridge-Loading Machines; and I do hereby declare the following to be a full, clear, and exact description of the invention, such as will enable others skilled in the art to which it appertains to make and use the same.

This invention relates to machines for loading cartridges for sporting shot-guns, in which the following elementary features are incorporated: first, two receivers or hoppers for containing the requisite quantities of powder and shot; second, a gate or gates containing the charging-chambers and operating with the receivers to regulate the escape of their contents; third, a support for the cartridge-shell adapted to hold the same mouth upward beneath the shifting gate or charger and permit the shell to be readily and expeditiously introduced to the machine to receive its charge and as readily and expeditiously removed after being charged.

My improvements in this class of machines consist, first, in the employment, in combination with the chamber or orifice of the shot-charger and the outlet of the shot-hopper, of an elastic or yielding sleeve or seat, whereby a pellet of shot, which would otherwise be caught between the parts and obstruct the rotation of the gate, is allowed to escape into the passage leading to the cartridge-shell; secondly, in the manner of attaching the guide which supports the cartridge-shell in an upright position while being loaded, the same consisting in pivoting the guide or support at or near its center to the machine-frame by a horizontal pivot, which permits it to be turned upon such pivot and its lower end diverted to one side of the base or shelf upon which the shell rests, the same being to permit of ready insertion of the shell to receive its charge and of its removal after being loaded; thirdly, in the employment, in combination with the oscillating guide, of a shifting or adjustable shelf or seat for supporting the base of the cartridge-shell, and susceptible of being raised and lowered with respect to a shoulder in the upper part of the guide, against which the

mouth of the shell abuts in order to adapt the machine to shells of varying lengths, the said shelf or seat consisting of a recessed button or head having a screw-threaded shank to 55 screw into a corresponding screw-threaded orifice in the lower part of the machine-frame, as hereinafter explained.

Minor details of my improvements will be 60 duly explained.

The drawings accompanying this specification represent, in Figure 1 an isometric elevation, and in Fig. 2 a vertical section, of a machine embodying my improvements. Fig. 3 is an under-side view, and Fig. 4 a plan, of the 65 vibrating gate or charger-block.

In said drawings, the frame of the machine is represented at A as composed of a cast-metal block or standard adapted to be clamped to a bench or table after the manner of this 70 class of machines in general, the upper rear corner of such standard being recessed at B for the reception of the vibrating reciprocating charger-block or gate, to be hereinafter described, the chamber B having a single outlet or 75 escape passage, C, at its front part, which communicates with a duct, D, leading downward to the locality occupied by the mouth of the shell-guide. The chamber B, in the present instance, is circular, and receives the lower end or mouth 80 of a can or vessel, E, erected upon the wall of the chamber, this can or vessel being divided by a partition, a, into two chambers or hoppers, F G, one of which is to contain a supply of powder and the other of shot, and both communicating with the chamber B at alternate 85 periods of time through the ports in the charger or gate, which are concentric with the outlets e f of the hopper.

The vibrating or reciprocating gate (to which 90 allusion has been made) is shown at H as composed of a flat plate, b, circular or segmental in shape, and having two ports or orifices, c d, formed in it, these orifices being arranged in the path of a circle struck from the pivot 95 of the plate b and being concentric with the outlets e f of the hoppers.

The pivot of the gate is shown at g as a vertical pin or screw passing upward through the bottom of the chamber B and screwing into 100 the bottom of the can or vessel E, while I represents a handle screwed to the periphery

of the gate and extending outward through a horizontal slot, *h*, in the wall of the chamber *B* into a position to be readily grasped by the operator, and by means of which the semi-rotations or vibrations of the gate are effected, the length of the slot being equal to the distance between the centers of the ports in the gate taken on a line concentric with the pivot of such gate, in order that the ends of the slot 5 may constitute stops to determine the extent 10 of movement of the gate in either direction essential to present its ports in succession to the outlet of the chamber.

To the under side of the plate *b* are secured 15 two boxes, *i j*, which coincide with the openings *c d* in the plate *b*, and constitute the chargers or charging-chambers, the united 20 lower surface of these boxes bearing upon the bottom of the chamber *B*, while the upper 25 surface of the plate *b* bears closely against the bottom of the vessel *E*. The chargers *i j* are arranged to coincide one with each of the outlets of the hoppers *F G* upon their respective sides, and both operate at alternate periods of time with the outlet of the chamber, and each has a sliding partition, *k*, operated by a screw, *l*, by which its capacity may be varied to increase or diminish its charge.

The guide to support the cartridge-shell is 30 shown at *J* as a straight tube having a trumpet-mouth and disposed upon or against the front face of the machine-frame, and being pivoted at about its center to the latter by a horizontal pivot, *m*, the position of this guide 35 when upright with respect to the lower end of the outlet of the duct *D* being such that its trumpet-mouth is situated immediately below such outlet.

To insure the proper vertical position of the 40 guide I may add to the frame of the machine a stop, against which the side of the guide abuts, and connect the guide and stop with a suitable spring to insure contact of the two; but I prefer a bolt hereinafter described.

45 In place of the stop and spring last described for holding the guide in an upright position, a horizontal spring-bolt, *v*, may be employed, secured to the lower part of the guide and operating with a socket in the machine-standard to insure the upright position, and with the side of the said standard to hold the guide in its inclined position either for the purpose of removing a loaded or entering an unloaded shell.

55 Below the guide-tube *J*, I dispose the shelf or seat which upholds the cartridge-shell while being loaded, such shelf consisting of a disk, *o*, constituting the upper part of a screw-threaded rod, *p*, which is screwed within a 60 vertical screw-threaded orifice, *q*, created in a bracket or ledge, *r*, of the frame *A*. By turning the rod *p* in one or the other direction the height of the shelf or seat with respect to the guide-tube or the interior ledge or shoulder, *s*, 65 of the same, against which the mouth of the cartridge-shell abuts, is raised or lowered, and

the machine thereby adapted to cartridge-shells of varying lengths.

In order that the operator may have a supply of wads readily at hand while loading cartridges, I employ a horizontal shelf, *w*, secured to the standard *A* and situated adjacent to or surrounding the mouth of the guide-tube and flush with the upper end of the latter. A supply of wads is to be placed upon this shelf, 70 and as one is needed it is pushed with the finger to and over the edge of the shelf and allowed to drop into the mouth of the guide-tube.

The rammer for driving wads into the cartridge-shell is shown at *K* as contained within a tubular head, *L*, constituting the upper front portion of the machine-frame, such rammer and head being disposed in alignment with the axis of the guide-tube *J*, and the rammer 80 being lowered by a blow of the hand or by a lever, *t*, pivoted at base to a standard, *u*, making part of the machine-frame, and fulcrumed upon or to the head of the rammer, the handle of the lever extending into a position to be 90 readily laid hold of by the operator.

The passage or port *d* in the gate *H* is, in the present instance, the shot-charger and the hopper *G* is the shot-magazine; and in carrying out one of the important features of my 95 improvements I line the said passage *d* with a sleeve of india-rubber or other elastic or yielding material, in order that, in the event of a pellet of shot being jammed between the edge of the mouth of the said passage and of the 100 outlet *f* of the hopper *G*, such lining shall yield and deflect the shot into and through the passage and into the duct *D*.

It is found in many instances, in the use of these machines as heretofore made, that a pellet of shot often becomes wedged between the unyielding surfaces about the mouths of the openings and the machine becomes inoperative. By the use of the elastic or yielding sleeve or its equivalent this cannot occur.

110 The elastic lining, instead of being in the gate, may be on the bottom of the shot-hopper *G* or chamber *B*.

The normal position of the gate is in one of its extremes, as governed by the handle and slot before named, and with one of its ports full open to the adjacent hopper and its other port closed by the bottom of the can or vessel.

The operation of this machine is briefly as follows, it being understood that before filling the hoppers with powder and shot care should be taken that the charger *i* for containing powder is full open to the powder-magazine, and the shot-charger *j* consequently closed by the solid portion of the bottom of the shot-magazine: The guide-tube *D* is now turned to one side, a cartridge-shell inserted through its lower end, and it is then returned to place in a vertical position, the head of the shell resting upon the disk or seat *o*. By turning 120 or moving the gate to its extreme opposite position the charge of powder contained in the 125 cartridge-shell is driven into the shell.

chamber or cell *c* is carried over and discharged into the duct *D*, and through the latter falls into the cartridge-shell contained in the guide *J*, the solid portion of the gate closing the outlet of the powder-magazine, while simultaneously with this movement of the powder-charger the shot-charger *d* arrives below the shot-magazine and is filled with shot. A wad is now placed in the mouth of the guide-tube *D* and driven down upon the powder by the rammer and returned to its elevated position. The gate is now turned to its full extent in the opposite direction, the result being that the charge of shot in the cell *d* is carried over and discharged into the duct, and through the latter into the cartridge-shell upon the powder therein, the solid portion of the gate keeping back the shot in the magazine, and a second wad is placed in the mouth of the guide-tube and the rammer again lowered to ram the wad upon the shot, when the loading of the shell is completed and it is removed. As the gate describes the last-named movement in discharging its charge of shot its powder-charger arrives beneath the outlet of the powder-magazine, and it becomes filled from the latter in readiness for a renewed movement of the gate in loading a second cartridge-shell.

In Fig. 2 of the drawings will be seen a peculiar construction of the interior of the shell-guide, which is intended to adapt the latter to both paper and metallic shells. In this case I form the upper interior part of the guide-tube with the peripheral shoulder *s*, of a diameter corresponding to the mouth of the paper shell, and when such paper shell is introduced it fits accurately to such shoulder. As paper shells are seldom or never reloaded, they do not become enlarged and vary in diameter with use.

Hence an arbitrary size of the interior of the guide-tube is all that is needed for paper shells, and the shoulder *s* supplies this need. With metallic shells, however, the case is different, as they are reloaded many times and they expand and increase in diameter under successive discharges. Hence a guide of uniform diameter would not answer, as they would be introduced or removed with difficulty. To remedy this objection I gradually increase the diameter of the interior of the guide-tube *J* for a short distance below the shoulder *s*, as shown at *c'*, the result of which is that the mouth of the metallic shell will always find a bearing within the tube.

I claim—

1. In a cartridge-loading machine, the combination, with the hopper-outlet passage and vibrating gate, of a rubber or other flexible elastic lining for said gate, substantially as set forth.
2. In a cartridge-loading machine, the combination, with suitable feeding and packing devices, of pivoted guide *J*, spring-pressed bolt *v*, and the recessed or socketed standard, substantially as set forth.
3. In combination with plunger *K*, guide *J*, seat *a*, hopper *E*, gate *H*, and table *W*, the block *A*, constructed to receive and hold all of said parts in their proper positions and places, whereby a single piece suffices for the whole frame, and the machine is made very compact and simple.

In testimony whereof I affix my signature in presence of two witnesses.

ORLANDO F. BELCHER.
